UNITED STATES PATENT OFFICE.

HENRI VIGNON, OF PARIS, FRANCE.

DRY CELL.

Application filed November 4, 1925, Serial No. 66,780, and in Great Britain December 3, 1924.

This invention is directed to improvements in dry-cell batteries.

The object of the invention is to provide a battery of this type constructed in such manner so as to provide a recess or reservoir for the reception of solution of sal ammoniac capable of entering the battery cell to revive or increase the activity thereof after having become deteriorated from use.

10 In the accompanying drawing, the figure represents a central, vertical sectional view through the cell.

The battery comprises a tubular container 1 of any suitable moisture repelling material, 15 and is formed with a bottom 2. Inserted in the container is a zinc sleeve 3, the upper end of which extends above the container 1, the purpose of which will be later explained.

A lining 4 of rolled blotting paper is inserted in the container, and within the confines of the sleeve 3, the lower end of this roll resting upon the bottom 2, while the upper end thereof is in the same plane as the upper end of the container. By rolling the 25 blotting paper a central opening 5 is provided which receives a cylinder 5' of the manganese.

The bottom 2 has a central depending lug 2' and in which is mounted a brass cap 3'. 30 Fitted in the cylinder 5' is the carbon electrode 2, the bore of the cylinder 5' accommodating said electrode which has its lower end engaged in the brass cap 3'.

A disk 11 of suitable porous composition 35 is placed within the sleeve 3 and rests upon the upper ends of the roll 4 and cylinder 5', and above this disk is placed a perforated

circular plate 8. A collar 12 encircles the upper extended ends of the sleeve 3 and interposed between the upper end of the container 1 and said collar is a rubber gasket 7. It will thus be seen that the extended end of the sleeve forms in conjunction with the plate 8 a reservoir 8' in which a solution of sal ammoniac is placed, the perforations 9' 45 of the plate permitting the solution to pass through the disk 11 and through the same for absorption by the roll 4 to distribute it to the cell in order to revive the same.

The container 1 and lug 2' are provided, 50 respectively, with extensions 10 and 12, the latter having an electrode 6 therein which connects with the cap 3' while the electrode 9 within the extension 10 connects with the sleeve 3.

Having thus described the invention, I claim:

An electric battery of the class described, comprising a container, a bottom for the container, a cap associated with the bottom, 60 a sleeve in the container having its upper end extended above the container to provide a reservoir, a bottom for the reservoir including a porous disk and perforated plate, an absorbent element in the sleeve, a cylinder of manganese in said element, an electrode within the cylinder and having its lower end engaged with the cap, and its upper end engaged with the disk, and electrodes engaged, respectively, with the sleeve 65 and cap.

In testimony whereof I affix my signature.

HENRI VIGNON. [L. S.]
